SINGLE STATION RANGE LIGHT APPARATUS

John R. MacKay, Packanack Lake, N. J., assignor
to Wallace & Tiernan Products, Inc., Belleville,
N. J., a corporation of New Jersey

Application April 18, 1947, Serial No. 742,419

15 Claims. (Cl. 177—352)

1

My present invention relates to a single station range light apparatus for indicating to an observer his position in respect to the center of a predetermined channel, whether that channel be over land, water or in the air, and also to a method of accomplishing these purposes.

Conventional range light practice which has been used for a considerable time in assisting navigators to locate themselves in the use of a waterway, such as a river or the entrance to a harbor, consists in providing a pair of lights to mark the channel, these lights being in horizontal alignment with the channel but with the rear light usually placed higher than the front light and a considerable distance in back of it, so that the navigator can use the range by keeping the lights vertically in line as he progresses into and along the desired channel. In order to prevent the lights from blending together and appearing as a single light, the vertical distance between the lights must be considerable. Furthermore, in order that the indication to an observer be sufficiently sensitive, the horizontal distance separating the lights must be considerable, often in the neighborhood of one-quarter to one-half a mile.

In many instances, it is impractical or too expensive to provide lighted ranges of the conventional type aforesaid. For example, sometimes high cliffs or river banks close to a waterway prevent the installation of a rear range light as the intervening high land would make it invisible to ships navigating the channel. In other cases, there is no land or other structure available on which either a front or a rear light can be installed. At times the site, which would be used for the erection of the rear range light, is in a city or on property, the rental or purchase of which would be prohibitive in cost.

Because of the above difficulties, as well as others, there has been a definite, unfilled demand for a single station range light, i. e., a light or group of lights which are all installed at one location, and which will give the navigator an accurate indication as to whether or not he is in a prescribed channel or waterway, and, if he is off his course, the direction in which he should steer his vessel in order to return to the desired course or channel. The fulfilling of this demand is a primary, general object of the present invention.

Some attempts have been made to solve this problem by the use of different colored lights. These attempts have, however, not been completely satisfactory for several reasons. A fur-

2

ther object of the present invention, therefore, is to provide a single station range light apparatus and method, which is independent of color.

It has been found, in the development of the subject matter to which the present invention pertains, that a characteristic series of intermittent periods of illumination is easily perceptible to the naked eye and serves efficiently to indicate to an observer the information intended to be conveyed. Thus a primary feature of the present method is to provide to an observer different programmed characteristic periods of light and darkness peculiar to the two sides respectively of the desired channel, so that by a rapid observation, an observer or navigator can quickly ascertain on which side of the center of the predetermined channel he is located at any instant.

By providing complementary characteristics 20 of light and darkness respectively on the opposite sides of the channel, i. e., by having one beam of light directed down one side of the channel and a beam of light directed down the other side, and suitably programming the periods 25 of illumination and intervening periods of darkness for each beam, then having the beams directed so that they will overlap, and further by providing that the periods of illumination down one side will correspond substantially to the periods of darkness on the other respectively, a central zone will be provided in which an observer will see a steady light. This central zone is a preferred channel which is normally intended for use. If then the characteristics on opposite sides of this steady light zone are different, for example a series of dots or relatively short lighted periods on the one side and a series of dashes or relatively long lighted periods on the other, an observer may quickly determine his 30 location in respect to the center of the channel. The provision of this method of illumination and apparatus providing it are further principal objects of the present invention.

As a particular method of working out the results generally mentioned above, it has been found and is set forth in detail hereinafter, that if a single light source be used in conjunction with light beam directing means effective to swing the beam between terminal positions, respectively on opposite sides of the center of the channel, the results described above can be satisfactorily attained. The provision of apparatus for effecting this result in various feasible ways is a further and more specific object of the present invention.

It has further been found that apparatus of the type aforesaid may be provided with means for controlling the lateral spread of the beam, which in conjunction with a control of the position and amplitude of the oscillation of the beam can be used to predetermine the outside safe limits of the channel by limiting the sector of illumination to safe portions of the channel. It can also be used to predetermine the angular width of the central portion thereof either by providing an overlap of the beams on the opposite sides of the center and thus providing the zone in which an observer will see a steady light as aforesaid, or, when the apparatus uses but a single light source which is oscillated from side to side, by providing an intervening zone between the beam areas on opposite sides of the channel, in which intervening zone an observer will merely see a quick flash as the beam is oscillated from one side of the channel to the other. The provisions of the above as to method and as to particular apparatus for carrying it out are further more detailed objects of the present invention.

Among the more specific objects of the present invention are to provide light beam moving means effective to swing a beam from side to side as aforesaid according to a predetermined programming schedule, which is repeated during successive equal intervals of time. From a broad point of view, such programming and operating means may be actuated by any substantially constant speed prime mover. It may take the form, as hereinafter set forth, of a cam-operated mechanism strictly mechanical throughout and preferably including a toggle over-center-throw mechanism, by which the oscillating portions of the apparatus are caused to dwell for substantial and predetermined periods at each end of their path of movement and to move from one end to the other with a relatively rapid motion. It may also include a prime mover operated programming means arranged to control electrically energizable solenoids, preferably in conjunction with holding means of a magnetic character, so arranged that power to the respective solenoids may be supplied by a programming switch mechanism and the oscillating portions or mechanism of the light beam directing means be retained at its terminal positions respectively by the magnetic holding or retaining means whenever the solenoids are not energized. The solenoid operated arrangement hereinafter described may also be used in conjunction with a toggle mechanism in lieu of magnetic holding means. The provision of apparatus for accomplishing these several purposes constitutes further detailed objects of the present invention.

It has also been found in conjunction with the development aforesaid that light beam directing means associated with a source of light will include basically as elements a reflecting mirror of some desired contour, usually parabolic, and some suitable lens means. In the event a parabolic reflector is used, the lens means need only be provided to serve the purpose of controlling the spread of the beam. By various arrangements of oscillating one of these three elements, i. e. the light source, the mirror and the lens means, in respect to the other two, or sometimes oscillating two with respect to the other one, the light beam may be directed as desired. The provision of various practical arrangements for effecting such oscillatory movement of a light beam for the purposes generally hereinabove set forth are further specific objects of the present invention.

Other and more detailed objects of the present invention will appear in the following detailed specification and will be pointed out in the appended claims, when considered in conjunction with the accompanying drawings, in which:

Figure 1 is a view principally in side elevation of a range light apparatus in accordance with the present invention, a part of the casing being broken away to show the interior construction, this form being one in which a mechanical over-center-throw toggle type oscillating means is used to oscillate the mirror reflector only;

Fig. 2 is a view of the apparatus of Fig. 1, taken substantially in plan, with a part of the housing broken away to show the interior construction;

Fig. 3 is a view of the apparatus of Fig. 1 substantially in end elevation as seen from the right in Figs. 1 and 2 and with portions of the housing broken away to show the interior construction;

Figs. 4 and 5 are fragmentary detail views in plan, illustrating the operation of certain of the oscillatory means for the apparatus of Figs. 1 to 3;

Fig. 6 is a detail view in plan, similar to Figs. 4 and 5, but showing a somewhat modified arrangement in which the oscillation is effected directly by the cam without the intermediation of the over-center-throw toggle mechanism;

Fig. 7 is a detailed view substantially in vertical section on the line 7—7 of Fig. 6;

Fig. 8 is a perspective view of a means by which a lampchanger as shown in Fig. 1 may be substantially universally adjusted as to position within predetermined limits;

Figs. 9 and 10 are vertical sectional detailed views of the subject matter of Fig. 8, taken on the lines 9—9 and 10—10 respectively of Fig. 3;

Fig. 11 is a fragmentary detailed view partly in elevation and partly in vertical section of a portion of the construction of Figs. 8 to 10;

Fig. 12 is a wiring diagram with some of the operating mechanisms shown diagrammatically, illustrating the electrical operation of the apparatus of the preceding figures;

Fig. 13 is a diagrammatic illustration showing the illuminated areas for the two beam positions when there is an over-lap of these beams at a central zone;

Fig. 14 is a view similar to Fig. 13 illustrating the illumination characteristics when the beam areas are spaced apart;

Figs. 15 and 16 are views corresponding respectively to Figs. 1 and 2, but showing a modified form of the invention in which the mirror-reflector is oscillated by a pair of opposed solenoids;

Fig. 17 is a detailed view showing some of the mechanism of Figs. 15 and 16 and particularly illustrating the magnetic holding means for preventing movement of the mirror-reflector when both solenoids are de-energized;

Fig. 18 is a wiring diagram similar to that of Fig. 12, but pertaining to the form of the invention of Figs. 15 to 17;

Figs. 19 and 20 are respectively an elevational view with parts in section and a plan view of a further modified form of the invention wherein the light source is oscillated, the mirror-reflector and lens means being held stationary;

Figs. 21 and 22 are views generally respectively similar to those of Figs. 19 and 20, but showing a further modified form of the invention in which the light source and the mirror-reflector are held stationary but the lens means is oscillated;

Figs. 23 and 24 are a further pair of views similar in general to Figs. 19 and 20, respectively,

but showing a form of the invention in which the light source is held stationary and the mirror-reflector and lens means are simultaneously and bodily oscillated in respect to the light source;

Fig. 25 is a fragmentary view, principally in plan, illustrating a further form of the invention, including means for changing the direction of the light beam at substantially a right angle within the range light apparatus; and

Fig. 26 is a fragmentary view, principally in elevation of many of the parts shown in Fig. 25.

Referring first to Fig. 13, a single station range light apparatus is indicated generally at 1, this apparatus being effective to direct a beam designated 2 down the right side of the channel as seen in the drawing and a beam designated 3 down the left side thereof. This result may be produced either by one or two sources of light, suitable light directing means being associated with the light source or sources, so as to produce the desired result as generally shown in Fig. 13. If then the beam 2 is so programmed, for example, as to give a succession of short flashes and the beam 3 to give a succession of long flashes, a person in the area illuminated by the beam 2 indicated by the area with broken hatch lines will know that he is on the right side generally of the center of the channel, while a person in the area of the beam 3 wherein the hatching is made with continuous lines will know that he is on the other or left side of the channel.

As shown, the beam areas overlap one another in a central zone 4. If then the periods of illumination in the area 2 are made in effect the reverse of or complementary to those in the area of the beam 3, a person located anywhere in the zone 4 will see a substantially steady light. This is so whether the range light apparatus uses one or more sources of light, at least from any reasonable distance therefrom, as two lights located close together will merge to the eye into a single spot of light at any substantial distance.

The lateral border lines of the zones 2 and 4 of Fig. 13 are in practice not usually exactly sharp lines so that the borders of the intermediate zone 4 are not usually in practice sharply defined. As a result an observer at the center of the channel, i.e. of the zone 4, will see a steady light as aforesaid. As such observer moves laterally in one direction or the other, he will commence to see the light characteristics of the zone 2 or 3, respectively, superimposed upon a continuous high intensity background of light. This modulation becomes more pronounced as the edges of the zone of continuous light are approached. If the observer continues to diverge from the center of the channel into the portions of the zone 2 or 3 not included in the overlap zone 4, the clear-cut light interval characteristics of the zone 2 or 3 are apparent, there being a progressively less background of continuous or residual light. This was demonstrated in practice by a small model constructed in general in accordance with the invention as herein disclosed and which operated on the same principle and wherein at a distance of about $\frac{1}{2}$ mile from the light, an observer located at the center of the channel, i.e. corresponding to the center of zone 4, saw a steady light, while movement 5 or 6 feet laterally in either direction resulted in the appearance of a characteristic indication depending upon the direction of such lateral movement. At about 20 to 30 feet one side or the other of the center, the characteristics of the lateral zone of light became distinct and clear-cut.

This light modulation is valuable in that it notifies an observer of his departure from the center light position long before he reaches the edges of the steady light zone shown at 4 in Fig. 13. The same effect is apparent when the beams 2 and 3 are given substantial lateral spread, so that the zone 4 is of substantial angular dimensions.

As above stated, there are particularly disclosed hereinabove complementary flash characteristics including a series of intermittent dots (code letter "E") on one side of the channel area, and a series of dashes (code letter "T") on the other side thereof. This combination is usually preferable. It is contemplated, however, in accordance with the present invention, that any different characteristic intermittent periods of illumination be provided on the opposite sides of the channel which will be preferably complementary to one another. Another such example of this type of programming could be to provide a succession of flashes corresponding to the code letter "A" on one side (dot-dash or short flash-long flash) and code letter "N" on the other side (dash-dot or long flash-short flash). Another possible combination would be to provide flashes corresponding to the code letter "K" on one side (dash-dot-dash or long flash-short flash-long flash) and code letters "I-T" on the other side (dot, dot-dash or two short flashes, long flash). Any feasible combination of different characteristics of flashes such as those herein suggested and others which will occur to those skilled in the art may be employed within the purview of the present invention.

By suitable lens and reflector apparatus combinations, the spread of the beams 2 and 3 may be controlled. A practical method of accomplishing it will however be set forth hereinafter. By controlling the spread in conjunction with the direction of the two beams 2 and 3, two things can be accomplished. First, the total illuminated sector can be determined as to the outside dimensions thereof considered in angular degrees; and second, the angular extent of the overlap zone 4 can be determined. Normally the zone 4 will be predetermined in angular width and position by the preferred portion of the channel intended for use.

While the results illustrated in Fig. 13 may be accomplished by two light beam providing means, each of which is stationary, it is preferred, in accordance with the present invention, to obtain these results by the use of a single light source with which is associated a means for laterally swinging the beam of light therefrom. The light from this source is usually concentrated in a relatively narrow beam of predetermined spread by light directing means including a mirror-reflector with or without lens means. In certain cases, however, such as a wide harbor entrance, or where the confines of an anchorage or other relatively large area is being marked, the beam used may be quite wide, possibly extending over a sector of 10 to 20° or more. If then there be some means for oscillating the necessary elements of these means so as rapidly to change the direction of the beam, the results illustrated in Fig. 13 will be attained. Under the circumstances, it is possible to provide an area as shown for the beam 2 in which an observer will see a series of dots, and an area as shown for the beam 3 wherein the observer will see a series of dashes, while in the zone 4 the observer will see a substantially steady light independent of the oscillation of the beam.

Referring now to Fig. 14 there is illustrated diagrammatically a variant of the arrangement of Fig. 13 in which a beam area 5 indicated by the series of vertical narrow figures represents a right-hand beam, and a beam area 6 shown as a series of vertically wide figures represents a left-hand beam, the areas 5 and 6 not overlapping in the middle. As a result there will be a central zone 7 in which an observer will merely see a quick flash of light each time the beam is oscillated from one side to the other. This quick flash in both directions is represented by the pairs of vertically very narrow figures. Vertical distances in this figure represent the durations of the periods of illumination. Here again the outside angular dimensions of the beam areas 5 and 6 may be made to conform to the dimensions of the channel, then the spread of the beam, in this case singular as there is but one source of light, can be adjusted to provide a central zone 7 of a selected angular width.

The provision of illuminating methods according to either Fig. 13 or 14 and whether effected by a single or multiple light source is to be considered within the purview of the present invention. Apparatus for providing illumination using a multiple source of light is illustrated and particularly described and claimed in my co-pending application Ser. No. 770,072, filed August 22, 1947. The present application is particularly described to cover these two embodiments of the invention generically and cover specifically that embodiment wherein but a single light source is used.

Referring now to Figs 1 to 3 of the accompanying drawings, there is illustrated a range light apparatus, the housing and bodily adjustments of which may be considered the same for all forms of the invention with the possible exception of slight changes in the dimensions and conformation of the housing which may be necessary to accommodate certain different mechanism.

The single station range light apparatus generally designated at 1 is intended to be mounted upon any suitable support as that diagrammatically shown at 8, by securing an under-base portion 9 of the apparatus 1 to the support 8 by a plurality of suitable means as bolts 10. Centrally of the base 9 is an upwardly directed screw stud 11 passing through an aperture in a lower base member 12 and provided with a suitable nut 13 to secure the bases 9 and 12 together. As it may be desired to effect a relatively fine angular adjustment between the bases 9 and 12, the under base 9 is provided with a laterally extending arm 14 into which is threaded a bolt 15 passing through an arcuate slot 16 in a lateral extension of the lower base 12 (Figs. 2 and 3). In this way the lower base 12 and all the upper parts carried thereby as hereinafter set forth may be angularly adjusted about the vertical axis of the stud 11 and this adjustment secured by the bolt 15 and the nut 13.

At its right hand end as seen in Fig. 1 the lower base member 12 is provided with a pair of upstanding hinge elements 17 into which extend the inner smooth ends of a pair of threaded pintle bolts 18 as best seen in Fig. 3. These bolts are threaded in alignment with one another through depending extensions 19 of a lower housing member 20. This lower housing member cooperates with an upper housing member 21 secured thereto by mating flanges and a plurality of bolts as indicated at 22 to house the operating parts of the range light apparatus.

Means are provided for controlling the angular

position of the housing members 20 and 21 in respect to the base member 12 about the common axis of the pintle bolts 18. For this purpose the base member 12 is provided with a pair of upstanding lugs 23 having inclined surfaces as shown at 24 in a common plane. The underside of the bottom portion or wall 25 of the housing member 20 is provided with a similar pair of depending lugs 26 having inclined surfaces 27 also in a common plane. Arranged to engage the surfaces 24 and 27 is a laterally disposed bar 28 through which is threaded a bolt 29. This bolt has an inner smaller diameter threaded portion 30 reversely threaded in respect to the portion 31 threaded through the bar 28, this inner portion being threaded through a pintle 31 which is carried by a pair of upstanding lugs 32 rigid or integral with the base member 12.

Thus upon rotation of the bolt 29 in one direction or the other the distance between the axis of the pintle 31 and that of the bar 28 may be varied at will. As the bar 28 is moved to the right as seen in Fig. 1, it acts upon the surfaces 24 and 27 to wedge them apart, thus tilting the entire housing 20-21 clockwise about the pintle bolts 18 and serving to adjust the beams downwardly. This adjustment when made may be secured by a pair of swing bolts 33 pivoted at their lower ends on a substantially horizontal axis as indicated at 34 to rearwardly extending lugs carried by the base member 12 and passing between the bifurcations of lugs 35 carried by the lower housing member 20, suitable nuts 36 being threaded on the swing bolts 33 and tending upon being tightened to move the housings 20-21 in a counter-clockwise direction about the pintle bolts 18.

From the above it will now be obvious that by suitably loosening the nuts 36, the angle of the beam can be vertically adjusted by the bolt 29 and the adjustment secured by tightening the nuts 36.

The construction above described is arranged for initial adjustment upon the installation of the device as a whole at a particular point where it is to be used. In order to permit of accurate alignment of the range light apparatus 1 with the channel with which it is to be used, a sight tube 37 may be provided along one side as shown in Figs. 2 and 3, this sight tube being supported by one or more suitable brackets 38 from the lower housing member 20 and containing either telescope means or simply a peep hole and pair of cross hairs spaced therefrom. The sight tube 37 is mounted on the housing parallel with the center line thereof so that this will be normally pointed down the center of the desired channel substantially in alignment with the center of the zone 4 illustrated in Fig. 13. The several adjustments previously described may then be made in order to assure that the apparatus is properly pointed. If desired, this sight tube, if in the form of a telescope, may be made removable, so as to prevent damage thereto during the subsequent use of the apparatus.

The housing formed by members 20 and 21 is provided with a suitable window, usually of plain glass as shown at 39, Fig. 2, which is suitably sealed in place by an annular retaining ring 40 bolted to the upper housing member 21, so as to protect the mechanism within the housing from damage by weather or other causes.

Inside the housing 20-21 is a light beam providing means which consists basically of three elements; first, a source of light here shown 41 as an electric light bulb 41; second, a mirror

reflector 42 which in most cases will be parabolic in form and, third, a lens means generally indicated at 43.

In the form shown in Figs. 1-3 the source of light, which is being used at any one time, will be located with its center of illumination substantially at the focal point of the parabolic mirror 42 so that the rays reflected from the mirror will be substantially parallel. In practice it is preferred to employ a light shield in conjunction with each light source as shown for example by the shield 160 associated with the several bulbs 41 and 50 in Figs. 1 and 2. Such a shield may be made of relatively thin sheet metal and be arranged for spring gripping engagement with the light socket. The purpose of these shields is to prevent substantially all light other than that which impinges upon the reflector from becoming visible to an observer. Without the use of such shields, a considerable amount of light may be reflected from the interior surfaces of the housing and mechanisms contained therein, which produces what may be called "residual light." This residual light is visible to an observer and tends to prevent the transmission of a clear cut signal as from an off-course position by providing a background of continuous light and thereby reducing the contrast.

The lens means shown comprises a pair of lenses 44 and 45, which are mounted in frames as shown and are each independently removable and replaceable. In general, each of these lens means, for example the lens means 44, is of such character as to provide a predetermined spread of the beam in a certain direction as vertical, while the other lens means, as the lens means 45, is arranged to provide a predetermined spread of the beam in a lateral direction. These lenses each consist of a single body of glass or other lens-forming material having one face formed as a plurality of substantially cylindrical surfaces of predetermined radii of curvature so as to provide the desired spread in a direction perpendicular to the axes of the cylindrical surfaces. Such lenses may be procured commercially so that per se they form no part of the present invention. The selection of the proper type lenses for use to give predetermined selected vertical and lateral spreads is, however, an element of the combination of the present invention. In this way by selecting a lens giving a desired vertical spread, it is possible in conjunction with the angular adjustment of the apparatus 1 by the bolt 29 to compensate for the vertical height of the location of the range light apparatus 1 in respect to a given water channel or for other similar purposes. In installations where the desired beam divergence is known and will be unchanged in use, the spread light lens used for effecting a desired spread of the beam may be used as the front lens 39 and the lens means 44-45 and the structure used in support thereof eliminated. Such a construction increases the efficiency of the light to some extent as transmission losses occasioned by the plain glass window are eliminated.

Another possibility, particularly adaptable to a situation where the desired spreads in vertical and lateral directions are both known, is to combine in a single lens the characteristics affording such predetermined spreads. Such lenses are known to the art and could be used either as a substitute for the lenses 44-45 in

a support used therefor, or could be used in place of the plain glass lens 39. Such particular lenses are not for general purpose applications as they do not afford the ability to vary the spreads with the facility afforded by the construction shown in Figs. 1 and 2 and including the separate lenses 44-45, each of which may be selectively replaced by other lenses having desired spread characteristics in vertical and lateral directions respectively.

If apparatus of this kind be used in guiding aircraft for example, wide vertical spread may be desired with a restricted lateral spread. Such a combination is possible with the apparatus disclosed. If on the other hand a wide lateral spread is desired, it can be obtained to cover substantially any angular zone reasonably to be met in practice.

As above generally set forth it has been found possible to oscillate the beam between its two laterally offset positions preferably by moving one or two of the three beam directing means in respect to the other or others thereof. This same result could also be effected, for example by oscillating the entire light beam providing means bodily, as oscillating the entire housing 20-21 and parts contained therein about some axis as the axis of the stud 11. The form of the invention shown in Figs. 1 to 3, for example, is a presently preferred form and employs for the purpose of oscillating the beam, the mechanical oscillation of the mirror-reflector 42, the light source and lens means being held stationary. It is usually preferred in this connection that the oscillation of the mirror-reflector be about a substantially vertical axis in alignment with the focal point of the reflector at which the center of illumination of the light source is located. In this way the characteristics of the beam are substantially unchanged by the oscillation or swing thereof from side to side. In other forms of the invention, hereinafter described, other or others of the three light beam providing elements are moved. The terms vertical and horizontal as herein used are intended as relative only and to refer to the showing of the drawings of a range light apparatus used in connection with a water channel. If the apparatus were used for some other purpose and at some other attitude or angle, the directions would be correspondingly changed.

Turning now to the form of the invention particularly shown in Figs. 1 to 3, the lens means 44 and 45 are mounted in suitable frames which are removably secured as by bolts 46 from a pair of brackets 41, which in turn are secured to the lower housing members as by bolts 48. It will be understood that as an initial or set up adjustment, or thereafter if necessary, the lenses 44 and 45 may be removed and replaced by others having desired spread characteristics in vertical or lateral directions respectively.

While it is feasible to provide but a single light source such as the electric bulb 41 shown, it is preferred in commercial installations to provide a plurality of electric bulbs mounted on a suitable lampchanging structure. The details of this lampchanger apparatus per se form no part of the present invention and may for example take any desired form, for instance any one of those shown in the patents to Wallace No. 2,054,013, Wallace & MacKay No. 2,195,374, MacKay 2,258,575, or others. It is merely desirable that some such structure should be provided, so that in the event of a burnout of the operating

11

bulb, the range light apparatus will not be put out of operation. This is important practically as structures of the type herein disclosed are adapted for use in relatively inaccessible positions where they normally receive attention and maintenance but infrequently.

As shown in the accompanying drawings, the lampchanger includes a rotor 49 carrying a plurality of electric bulbs the operative one of which is shown at 41 and the remainder at 50. The rotor is mounted for rotation about a substantially horizontal axis in respect to a supporting structure 51 which carries a suitable motor, by which the apparatus may be operated when necessary, and the electrical connection means associated therewith. This means is best illustrated in Fig. 12 wherein line wires 52 and 53 are supplied with electric energy from a battery 54 or other source thereof under control of a master switch 55. Connection is made across the lines 52—53 to the operating bulb 41, in series with which is a solenoid coil 56 normally energized during the time the bulb 41 is operative and until it burns out. Upon burn-out of the bulb 41 at the operative position, the solenoid coil 56 is de-energized permitting the armature 57 thereof to move by gravity or under the force of a spring (not shown) to close a circuit between contacts 58 and 59 and thereby to complete a circuit through a motor 60 diagrammatically shown in Fig. 12 and in practice located within the supporting structure 51. This motor is suitably geared to rotate the rotor 49, which is indicated in Fig. 12 by a gear 61 carried by the rotor and to bring another one of the bulbs 50 to the position of the operative bulb 41. Suitable means are provided, upon a good bulb attaining this position, for connecting this bulb across the lines 52—53 in series with the solenoid coil 56. As soon as a good bulb reaches the operative position, a circuit is completed through it and the solenoid coil 56 is energized, so as to open the circuit between contact points 58 and 59 and stop the operation of the motor 60. This is done by providing a contact member as shown at 62, Fig. 3, spring pressed to engage in any one of a plurality of notches 63 in a drum portion of the rotor 49, in the bottom of each of which notches is a conductor connected to a bulb which will be at its operative position (as shown for bulb 41) when the conductor is engaged by the combined detent and conductor element 62. The other terminal of each bulb is grounded and is always connected to the other side of the line. The arms holding the sockets and the bulbs and forming a part of the rotor 49 of the lampchanger are preferably metallic bands which are located edgewise in respect to the path of the light from the reflector to the lens means previously described, so as to minimize the obstruction of light.

Means are provided for mounting the lampchanger generally indicated at 49—51 so as to provide substantially a limited but universal adjustment for the position of the operating source of light shown as the bulb 41. By this means the center of illumination of the bulb may be adequately adjusted to bring it substantially to the focal point of the mirror-reflector 42. For this purpose the bottom wall 25 of the lower housing member 20 is provided with an upstanding supporting portion 64, Figs. 1 and 8 to 11. Located and supported upon the portion 64 is an angle

12

member 65 which is provided with a downwardly directed stud 66, Figs. 8 and 9, arranged to move in a slot 67 formed in the portion 64 and directed forwardly and rearwardly substantially parallel to the direction of the center line of the beam or that of the channel. The angle 65 is retained in place on the portion 64 by a pair of threaded bolts 68 which pass through elongate slots in the horizontal web of the angle, which slots are disposed in a forward and rearward direction, i. e. perpendicular to the longitudinal extent of the angle 65. These slots are shown in part at 69, Fig. 8. Disposed intermediate the heads of the bolts 68 and the horizontal web of the angle 65 are compression springs 70 and if desired washers 71. The angle 65 is thus resiliently secured to the supporting portion 64.

At its ends the angle 65 is provided with a pair of longitudinally directed slots 72. Passing through these slots are a pair of bolts 73 having capstan heads, as shown, for the insertion of a suitable manipulating tool and further having eccentric portions 74 of substantially the thickness of the horizontal web of the angle 65, these eccentric portions being located in the slots 72. These bolts 73 are suitably threaded into the base portion 64. Thus by rotating the capstan bolts 73 the angle 65 may be moved in a direction parallel with the slot 67, this action taking place if both bolts 73 are rotated in the same direction and amount. Another possible adjustment is one in a horizontal plane about the axis of the stud 66, which may be effected by a differential movement of the eccentric capstan bolts 73. Any combination of these two movements may be effected within the limits of adjustment afforded by the eccentricity of the portions 74. The adjustment when made is secured against accidental displacement by the bolts 68 and the springs 70 associated therewith.

Secured to the angle 65 is another angle 75 having its vertical leg or web secured to the vertical leg or web of the angle 65, and having its other or horizontal leg or web arranged to support the structure 51 of the lampchanger. Similar arrangements are provided for adjustment between the angles 65 at 75 as between the angle 65 on the one hand and the supporting portion 64 on the other. For this purpose the vertical leg or web of the angle 75 has a vertical slot 76 therein into which projects a stud 77 carried by the vertical leg or web of the angle 65. Bolts 78 are provided corresponding to bolts 68 and similarly provided with compression springs 79 corresponding to springs 70 aforesaid. The bolts 78 pass through vertically elongated slots 80 in the vertical leg or web of the angle 65 and are threaded into the angle 75 as shown in detail in Fig. 10. At its ends the angle 65 has inwardly projecting slots 81 with which cooperate eccentric portions 82 of capstan bolts 83, corresponding to the capstan bolts 73 above described.

By suitable adjustment, either simultaneous or differential, of the capstan bolts 83, the angle 75 may be moved vertically in respect to the angle 65, by simultaneous adjustment of the screws 83, or may be tilted in respect to the angle 65 about the center of the stud 77, by differential adjustment of the screws 83.

The net result of these adjustments for the supporting means for the lampchanger is that the lampchanger is bodily substantially universally adjustable in three directions within the limits of the adjustment means provided so as to

position the center of illumination of the operating bulb 41 at the focal point of the mirror-reflector 42 or at any other particular desired position within the limits of adjustability provided.

The main operating construction for moving the beam laterally, which in the form of Figs. 1 to 7 is effective solely to oscillate the mirror-reflector will now be described. Basically this construction serves to support the mirror-reflector 42, so that it is capable of oscillation about a substantially vertical axis as shown in the accompanying drawings, which axis if extended would pass through the focal point of the mirror, i.e. the point at which the center of illumination of the bulb 41 is located.

This construction is carried by a suitable base 84 which may be secured as by bolts 85 to the bottom portion 25 of the lower housing member 20. Secured to the base 84 is a bracket 86 carrying a stationary vertically disposed pintle shaft 87, the axis of which is the axis of swing of the oscillating portions of the apparatus, and which axis is below and in vertical alignment with the center of illumination of the bulb 41. Mounted for free oscillatory movement about the axis of the pintle shaft 87 is a rearwardly extending actuating lever 88, hereinafter more particularly described, which is carried by a collar 89 surrounding the shaft 87. Above collar 89 is a similar collar 90 carrying the rearwardly extending pointer lever 91 and also carrying secured thereto the mirror reflector 42. This construction serves to mount the mirror-reflector for its oscillatory movement as generally hereinabove described.

The rear end of the lever 91 is formed as an indicator pointer as shown at 92, and it may be further provided if desired with a suitable index mark for cooperation with a stationary scale 93, which may be suitably graduated in units of angular measure, so as to indicate the terminal positions of the swing of the beam which are predetermined and adjustably controlled, as more particularly hereinafter described.

Means are provided for limiting the extent or amplitude of the lateral swing of the beam by limiting the angular oscillation of the mirror-reflector 42 and the lever 91. For this purpose a pair of stop screws 94 and 95 are provided (see Figs. 2, 4, 5 and 6), which are supported by suitable members or brackets 96 carried by the base 84, each stop screw being provided with a usual lock nut for securing the adjustment when made. A suitable bumper means 161 may be secured to the lever 91 for engagement with the stop screws 94 and 95. These screws 94 and 95 are in horizontal alignment with a part of the lever 91 so that one or the other is engaged by this lever at its opposite terminal positions. The angle of the beam may be indicated by the scale 93 cooperating with the rear end 92 of the lever 91, so as to enable the stop screws 94 and 95 to be accurately adjusted.

The means for oscillating the lever 91 and the mirror-reflector 42 comprises, in general, two series of mechanism, first an over-center-throw toggle type mechanism for oscillating the lever 91 and the mirror-reflector from the lever 88, and, second, a motor driven cam type mechanism for oscillating the lever 88. These mechanisms will be described in the order named.

The lever 88 is provided with a toggle member 97 pivoted thereto on an axis shown at 98 and provided with a bumper member 99. The forward or right-hand end as seen in Figs. 2, 4 and 76

5 of the toggle member 97 is connected to a depending stud carried by the lever 91 through a tension spring 100, it being noted that the depending stud at the left-hand end of the spring 100, as seen in Fig. 1, is to the left of the axis 98 for the toggle member 97. The toggle member 97 is provided with an arcuate slot 101, the center of which is the axis 98; and a suitable stud projects from the lever 88 through the slot 101, so as to limit the swinging movement of the toggle member 97 with respect to the lever 88. Suitable adjustable stops 102 and 103 are provided in upstanding projections from the base 84 cooperating with the bumper member 99 as shown at the upper portion of Fig. 5 and the lower portion of Fig. 2 for limiting the movement and fixing the terminal positions of the parts.

Thus as the lever 88 is moved from the position shown in Fig. 2 through that of Fig. 4 to that of 20 Fig. 5, the lever 91 is swung from its lowermost position in Fig. 2 to its uppermost position in Fig. 5. This action occurs as follows: as the lever 88 moves downwardly or in a counter-clockwise direction, the toggle member 97 is rotated in a 25 counter-clockwise direction about the axis 98 by the stop 103. After this movement has progressed a sufficient distance so that the center line of the spring 100 passes across the line connecting the axis 98 and the point of connection of the 30 spring 100 with the toggle 97, the toggle quickly swings completely to the position shown in Fig. 5, the spring 100 now being effective to move the lever 91 and the mirror-reflector carried thereby quickly from the Fig. 2 position to the Fig. 5 position. 35 In Fig. 4 is shown an intermediate position of the lever 88. At this position of this lever the toggle has not moved over its center so that the lever 91 and the mirror have not changed in position. There will result a rapid movement of the lever 91 from one side to the other irrespective of a relatively slower movement for the lever 88.

While there is particularly shown and described herein but one type of over-center-throw toggle mechanism, other types of mechanism for securing substantially the same results have been designed and are contemplated for use, if desired, in lieu of the one particularly disclosed. Such other types will occur to those skilled in the art as equivalents of the construction particularly disclosed and are to be considered within the purview of the present invention.

For oscillating the lever 88 to effect movement of the mirror as aforesaid, there is provided as 55 shown in Figs. 1 to 7 and 12 a cam 104 rotatable about a vertical axis and arranged to engage a suitable cam roller 105 carried by the lever 88. The cam roller 105 is retained in engagement with the cam 104 by a tension spring 106 extending between the left-hand or free end of the lever 88 and a suitable anchorage 107.

Means are provided for rotating the cam at a 60 substantially constant angular velocity. For this purpose any suitable prime mover may be employed. The one presently preferred as to the form of the invention shown in Figs. 1 to 3 and 12 is of the constant speed electric motor type. As shown, there are two such motors 108 and 109, both of which are connected to drive the cam 104 through suitable gears 110 and 111 respectively, both meshing with a gear 112 carried rigidly with the cam 104 on a common shaft therewith. Each of the motors 108 and 109 may be of a known or conventional type, such for example as those shown in the patents to Wal-

lace and MacKay No. 2,181,841, and to MacKay No. 2,181,842, both granted November 28, 1939. Other types of prime movers could, if desired, be used for this purpose, those referred to having been found to be eminently satisfactory. Each motor 108 and 109 is connected to its respectively associated gear 110 and 111 by a spring ratchet arrangement diagrammatically illustrated at 113 and 114 respectively (see particularly Fig. 12). The arrangement here provided is such that normally power will be supplied to both motors and both will drive the cam 104 simultaneously. However, should one motor fail for any reason, the cam and ratchet arrangement 113 and 114 respectively associated therewith will act as a free wheeling device, permitting the good motor to drive the cam without, at the same time, being required to rotate the rotor of motor which has failed. While electric motors are specifically contemplated for use on the device of the accompanying drawings, the purposes of the invention may be attained by the use of any suitable prime mover including those driven by other sources of power, such, for example, as spring or weight driven motors. Any suitable prime mover connected to drive a cam such as 104 at a substantially constant speed is to be considered within the purview of the present invention.

As shown in Fig. 12, the motors 108 and 109 are connected across the power supply line 52 and 53 so that when the master switch 55 is closed, both motors will be placed in operation. While the electrical connections are not illustrated in Figs. 1 to 3, it will be understood that they are suitably arranged substantially as diagrammatically shown in Fig. 12 and that power may be supplied to the entire apparatus through a junction or switch box generally illustrated at 115, Fig. 3. The master switch 55, if one is provided as shown, may be located in this box or at any other convenient point. If desired this switch may be operated by the amount of daylight in the vicinity by a "sun switch" apparatus of any type desired as those now in use in connection with unattended marine beacons. It is contemplated that any desired source of electrical power, including batteries or commercial power supply lines, may be employed for supplying the energy to operate the device as hereinabove described.

In Figs. 6 and 7 there is shown a slight modification of the apparatus wherein the action of the over-center-throw mechanism hereinabove described is in effect dispensed with and the levers 88 and 91 arranged for movement substantially as a unit and directly by the cam 104. For this purpose, the lever 91 may be provided with a laterally and downwardly extending arm 116 which carries a set screw 117 arranged to bear upon one side of the lever 88 and suitably adjustable to align these levers. Connected between a further depending portion of the arm 116 and an arm depending from the lever 88 is a tension spring 118 constantly urging the lever 88 into contact with the set screw 117. This arrangement will tend to keep the arms 88 and 91 in a predetermined position in respect to each other. Under these circumstances, the spring 100 is unnecessary and is normally removed.

In operation the position of the lever 88 may be directly controlled by the cam 104, while the limits of movement of the arm 91, carrying the mirror-reflector, is determined by the stop screws 94 and 95, independently of a possible additional movement in either or both directions of the lever 88 by the cam 104. For example, at the further-

most counter-clockwise position of the lever 91 and mirror-reflector 42, the position of these parts may be determined by the stop screw 95 even though the cam roller 105 is not then in contact with the small diameter portion of the cam 104. At the other or clockwise position of the parts, the cam roller 105 may be moved to an extreme position by a high point or zone of the cam 104. If, however, this position is further in a clockwise direction than the limit of movement of the lever 91 as determined by the stop screw 94, the latter determines the position of the mirror and the lever 88 is permitted to move under the control of the cam, stretching the tension spring 118. For the purposes of this operation, the stop screws 102 and 103 will normally be backed off to inoperative positions so as not to have any effect in controlling the movement of the parts.

Referring now to the form of the invention shown in Figs. 15 to 18 inclusive, there is provided an apparatus for the same general purpose as the form previously described, the arrangement differing essentially in that the means which operate to move the mirror-reflector 42 from one side to the other include a pair of opposed solenoids, preferably arranged in conjunction with a holding means so that once the mirror-reflector is moved to one of its terminal positions, both solenoids may be de-energized and the mirror-reflector retained against accidental displacement at the position to which it is moved.

The arrangement for mounting the mirror-reflector for this form of the invention is essentially the same as that previously described with the exception that there is no lever corresponding to the lever 88, while the mirror-reflector 42 and its supports are mounted upon a lever 119 which corresponds generally in function to that of the lever 91 hereinabove described and similarly cooperates with a sector 120 corresponding generally to the sector 93 and being similarly graduated. The lever 119 may be provided with a bumper means 121 arranged to engage one or the other of a pair of stop screws 122 and 123 corresponding respectively in function to the stop screws 94 and 95 and similarly carried by suitable brackets extending upwardly from the base 84, this base being given the same number as above for purposes of convenience.

Suitably supported from the base 84 as by a bracket 124 are a pair of opposed solenoids 125 and 126. These solenoids as shown are on different levels for convenience of construction and have their respective armatures connected to a part moving with the mirror-reflector by flexible metal strips 127 and 128 respectively, the armatures in these cases being concentric with the solenoid coils. Each of the strips 127 and 128 is shown connected with a part of the mirror base by a screw or similar fastening means 129 arranged at a point distant from the respectively associated solenoid. Each solenoid is arranged when energized to draw its associated strip 127 or 128 inwardly, i. e. toward the solenoid energized.

In this case electrical energy for energizing the respective solenoids is controlled by a pair of cam operated switches generally indicated at 130 for the solenoid 125 and 131 for the solenoid 126 (Fig. 18). These switches are respectively controlled by a pair of cams 132 and 133, both mounted upon the shaft of a substantially constant speed prime mover 134 which may be an electric motor of the same type as the motors 108 and

109 hereinabove described. Thus referring to Fig. 18, the motor 134 is connected across the supply lines 52 and 53 which are energized whenever the master switch 55 is closed. This will rotate the shaft carrying cams 132 and 133 continuously and at a substantially constant speed. As shown, the switch 130 is closed by its associated cam 132 which would serve to energize the coil of solenoid 125 to move the mirror-reflector 42 from the position shown in Fig. 18 in a clockwise direction to its other terminal position. The reverse action would take place when the mirror-reflector is at its other position and the solenoid 126 is energized by the closing of the switch 131 by its associated cam 133.

In order that power need not be supplied to one or the other of the solenoids continuously, which is important where a device of the character described is operated by batteries rather than a commercial source of power, means are provided for holding the mirror-reflector and associated means in either of their terminal positions when both solenoids are deenergized. For this purpose the lever 119 carries therebeneath a member 135 of magnetic material such as soft iron. Suitably supported upon the base 84 is a permanent magnet 136 which is U-shaped and has its ends or poles upturned as shown at 137 and 138. The member 135 may be suitably rotatably adjusted in respect to the lever 119, so that at the terminal positions of this lever, one end or the other of the member 135 will approach adjacent to, but preferably will not touch, one of the poles or ends 137 or 138 of the permanent magnet 136. As shown in Fig. 17 for example, the member 135 is adjacent to but not touching the magnet pole 138. The strength of this permanent magnet is such as to prevent undesired dislocation of the lever 119 and the mirror-reflector 42, while permitting the mirror-reflector to be moved from either of its terminal positions to the other upon the energization of the appropriate solenoid 125 or 126.

It is also contemplated that if desired a combination of toggle over-center-throw means as generally hereinabove described may be made with solenoid operation instead of cam operation so that the solenoids are effective to throw the toggle means over-center from one side to the other, while the toggle means per se serve to retain the parts in either of their terminal positions during dwell periods in which the solenoids may be both de-energized. This eliminates the necessity of using a magnetic holding means as shown at 135 to 138, Fig. 17, in conjunction with solenoid actuation.

It will be seen that by the means shown in connection with Figs. 15 to 18 and cams 132 and 133 of the appropriate shape the beam may be swung from one side to the other and its dwell times at each of its positions predetermined in accordance with any desired programming schedule, which schedule is repeated at the ends of uniform time intervals. In this case the interval is that consumed by a single revolution of the cam shaft carrying cams 132 and 133. It will be understood that with the exception of the parts specifically described as to Figs. 15 to 18, the remaining portions thereof may be the same as those described for the form of Figs. 1 to 3.

Referring now to Figs. 19 and 20 there is shown a form of the invention where another element of the beam providing means other than the mirror-reflector hereinabove described is oscillated, so as to direct the beam from one side to the other.

In this case, the mirror-reflector and the lens means are both held stationary but the source of light is oscillated in respect to both.

For this purpose, the center of illumination of the light source, here shown as an electric bulb 139, corresponds generally to the bulb 41, but is arranged so that it will not be exactly in the focus of the mirror-reflector 42, but rather somewhat closer to the mirror-reflector than its focal point and arranged to oscillate from side to side. The mirror-reflector 42 instead of being mounted upon the lever 91 as in Figs. 1 to 3 is mounted upon a bracket means, which freely straddles the levers 91 and 88 and which is secured to the base 84 by bolts 140 or any other suitable means, portions of the bracket supporting the mirror being shown at 141. In this form of the invention a pivot shaft 142 replaces in position and function the shaft 87 shown in Figs. 1 to 3 and is shown as arranged to be oscillated by means essentially the same as that particularly described in connection with that form of the invention. For this reason these means, to the extent shown, are given the same reference characters. Here the shaft 142 is arranged for rotation in respect to a stationary bracket portion 143 which corresponds to the bearing part of the bracket 86 shown in Fig. 1. The shaft 142 is itself oscillated by being pinned or otherwise secured to the lever 91 as at 144. At its lower end the shaft 142 is suitably secured to a carriage structure 145, which is provided with suitable rollers 146 resting upon a part of the base 84 or a hardened plate carried thereby. The carriage structure 145 has suitably secured thereto the lampchanger structure 51 which has a rotor portion 49 as previously described and may be essentially the same as that described in connection with Fig. 1, the major difference being that the entire lampchanger structure is here oscillated so as to oscillate the center of illumination of the active source of light shown as the bulb 139. It will be understood that the electrical leads to the lampchanger will be of some flexible character to permit of the movement thereof in any usual or known manner. With the exception noted, the device of Figs. 19 and 20 is substantially the same as that of Figs. 1 to 3, the oscillation of the light source here being relied upon to effect a swinging of the beam and the mechanism for programming and actuating that swing being substantially the same as previously described. It will be understood also that a solenoid operated means as shown in and described in connection with Figs. 15 to 18 could be used to oscillate the carriage structure 145 of this form of the invention and that such a combination is to be considered as within the purview thereof.

Referring now to Figs. 21 and 22 there is shown another form of the invention wherein the oscillation of a lens means is employed for effecting the swing of the beam, the light source and the mirror being maintained stationary. In this form of the invention there is shown a light source 41 carried by a lampchanger rotor 49, which is in turn rotatable in respect to a lampchanger structure 51, essentially the same as previously described in respect to Figs. 1 to 3.

The mirror in this case shown at 147 may be of a somewhat different contour than that shown at 42 in Figs. 1 to 3 and hereinabove described

in that a substantially spherical mirror is contemplated for use in this form of the invention. The lens means herein generally indicated at 148 preferably includes one or more optical elements for concentrating the beam in a desired spread area and thus is somewhat different as to the optical characteristics of the lens means than in previous forms of the invention. However, inasmuch as lens means for effecting such desired results are known, they will not be here described in detail, it being understood that any lens means effective to concentrate a beam from a light source located substantially at the center of curvature of a spherical mirror may be employed.

In this case the mirror 147 is suitably supported by the rigid structure including bracket elements 141 as in the case of the mirror 42 in the form shown in Figs. 19 and 20. The actuating means in this case is effective to oscillate the lens means 148 about the axis of a shaft 149 corresponding generally to the shaft 87 of the form of Figs. 1 to 3 and the shaft 142 of Figs. 19 and 20. In this case, however, the shaft 149 may be held stationary and the hub portion of the lever 91 surrounding this shaft, provided with a specially shaped bracket extension 150. At its outer end the bracket extension 150 carries a shaft 151 secured thereto as by a nut 152 or other suitable means, the shaft 151 in turn rigidly carrying a supporting structure 153 by which the lens means 148 is carried.

Thus as the lever 91 is oscillated by means shown as substantially identical to that described for the Figs. 1 to 3 form of the invention, the bracket, shaft and support means 150, 151 and 153 will be correspondingly oscillated as a unit to oscillate the lens means 148 in respect to both the source of light shown as the bulb 41 and the mirror 147. This will effect a swing of the beam with the same results as hereinabove described. Again it will be understood that the solenoid actuating means illustrated in Figs. 15 to 18 could be used, if desired, with this form of the invention.

While there is shown but a simple stationary support means 154 for the lampchanger structure 51, it is contemplated that suitable adjustable means as shown in Figs. 1 to 3 and 8 to 11 and described in detail in connection therewith may if desired be employed.

Referring now to the form of the invention shown in Figs. 23 and 24, there is provided an apparatus essentially similar to that of Figs. 21 and 22 with the exception that here the mirror as well as the lens means is oscillated. Thus the mirror and the lens means are simultaneously and bodily oscillated as a unit, both in respect to the light source, which in this case is stationary as in the form shown in Figs. 21 and 22 and described in connection therewith. Here again a substantially spherical mirror 147 is shown as in the form shown in Figs. 21 and 22. If desired, however, a parabolic form of mirror could be used as shown and described for Figs. 1-3 and 15-18. The lens means and the parts for moving it are given the same numbers as in the case of Figs. 21 and 22 due to their essential similarity. Substantially the only difference in this case from the form of Figs. 21 and 22 is that the mirror 147 is here mounted directly upon a part of the lever 91 rather than upon a sta-

tionary support as in the case of Figs. 21 and 22. As between these two forms, i. e. Figs. 21 and 22 on the one hand and Figs. 23 and 24 on the other, the latter is usually preferred as the optical characteristics of the beam in its oscillation are maintained under better control. On the other hand it is contemplated that either of these forms will be effective in use. Similarly this form of the invention may also employ a solenoid actuating means as disclosed in Figs. 15 to 18.

In Figs. 25 and 26 there is illustrated a form of the invention wherein a single source of light shown at 170 is employed in conjunction with a means for collecting light from this source and directing it as a beam. In this case this means is illustrated as a parabolic mirror 171 and the beam of light indicated by broken lines 172.

The light source 170 may be one of a plurality of electric bulbs mounted on a lampchanger generally indicated at 173 which may be of the same type as illustrated in Fig. 1 at 49-51, and may be suitably mounted upon a base as particularly described for the lampchanger in Fig. 1 et seq.

Means are provided in conjunction with this form of the invention for changing the direction at which the light beam is projected by a substantially right angle and then for oscillating the beam by varying this angular change in direction. For this purpose there is illustrated a plane or other suitably shaped mirror 174 which may be suitably mounted by a bracket 175 on a lever such as that shown at 91. The lever 91 may be mounted and oscillated in the same way as the correspondingly numbered element of the Fig. 1 form of the invention. The parts similar to those of Fig. 1 et seq. are given the same reference numbers. It is contemplated, however, that any suitable means for oscillating the mirror 174 may be employed, including a plain cam operation, without the necessity of the interposition of an over-center-throw mechanism as herein shown, or alternatively, a solenoid operated oscillating means as shown and described, for example, in connection with Figs. 15 to 18 inclusive.

With the arrangement shown, the mechanism used for oscillating the mirror 174 may be relatively light in construction as the mirror itself is relatively light in weight and hence requires little power to move it. In addition to this, due to the well-known laws of light reflection, it is necessary only to oscillate the mirror through half the angle through which the beam itself is oscillated. This may be taken into account by a suitable graduation of the scale shown at 176 in such a way that the indicia on this scale serve to indicate the actual degrees through which the beam from the entire apparatus is oscillated rather than the degrees through which the mirror 174 is oscillated.

While the arrangement shown in Figs. 25 and 26 provides for a substantially 90° change in direction of the light beam, this is not per se essential, as other degrees of angular change effected by a mirror or equivalent means for changing light directions may be employed within the purview of the present invention. Also, while but a single change in direction of the light beam is here illustrated, multiple changes may be employed if desired following the principles herein generally taught. Furthermore, while the arrangement here shown is to direct the original beam indicated by the lines 172 in a horizontal direction, the original beam direction may be

vertical or at some other angle if desired and one or more mirrors or other light beam direction changing means suitably disposed to project the beam from the apparatus in the desired direction.

Further, if it be desired, the mirror 174 may be given such a configuration as to control the spread of the resulting beam. In this way, the use of the spread light lenses 44 and 45 may be dispensed with.

While the device in its various forms has been described primarily as one for use in guiding ships over navigable waters, it is specifically contemplated that apparatus of this same general type could be used for guiding persons or vehicles across essentially trackless areas such as those in a desert country. Furthermore, apparatus of this kind could be employed in guiding airplanes either along a course or toward a landing, considering the direction of guidance as generally lateral or in a horizontal plane so as to indicate to a pilot of an airplane whether he is in a desired course or channel or to one side or the other thereof laterally. On the other hand, it is further contemplated that if desired, apparatus substantially in accordance with the present invention could be mounted at substantially right angles to that in which the present device is particularly arranged as herein shown, so as to indicate deviations from a desired channel in a vertical plane. If then the desired channel were, for example, an inclined glide path to be employed by airplanes in descending to a landing at an airport, a device according to the present invention could be used to indicate to the pilot whether he was above or below the desired glide path at any instant. Any such use or others for which the apparatus of the present invention is reasonably susceptible and the method of using it are to be considered within the purview of the present invention and within the scope of the appended claims, which are to be construed validly, as broadly as the state of the prior art permits.

I claim:

1. Single station range light apparatus for visually indicating to an observer his position in respect to the center of a predetermined channel, comprising at least one source of visible light located substantially in a vertical plane containing the center of said channel and substantially in prolongation thereof, light beam directing means associated therewith for directing beams therefrom with their center lines in predetermined directions and having predetermined restricted lateral angular spread about said center lines down each side of said channel respectively, said light beam directing means including lens means for predetermining the lateral spread of said beams, means for independently adjustably locating the sector illuminated by each of said beams by adjustably varying the position of said center lines in coordination with the center and lateral outside safe limits of said channel to restrict said beams to predetermined portions of said channel considered safe for use, and programming means independent of said locating means for automatically controlling the time periods during which a visible light beam is directed down one side of said channel and for similarly controlling substantially complementary time periods during which a visible light beam is directed down the other side of said channel, said programming means being constructed and ar-

ranged to provide dissimilar and characteristic intermittent periods of illumination and darkness on opposite sides of said channel respectively, whereby an observer may visually ascertain on which side of the center of said channel he is located.

2. Single station range light apparatus for visually indicating to an observer his position in respect to the center of a predetermined channel, comprising a single source of visible light located substantially in a predetermined plane containing the center of said channel and substantially in prolongation thereof in said plane, light beam directing means associated with said light source for restricting the area of illumination thereof to a predetermined relatively narrow zone in a lateral direction, perpendicular to said plane, means for relatively moving said light source and at least a part of said light beam directing means to swing said beam back and forth between a first position in which it is directed down one side of said channel with the center of said beam on one side of the center of said channel, and a second position in which it is directed down the other side of said channel with the center of said beam on the other side of the center of said channel, means for adjustably limiting said relatively moving means for controlling the amplitude of the swing of said beam between said two positions, thereof, fixed support means, and means adjustable in respect to said support means and independent of said adjustably limiting means for adjusting the position of said entire range light apparatus about a substantially vertical axis in respect to said support means so as to coordinate the position and amplitude of the area illuminated to the dimensions of the channel in respect to the location of said range light apparatus, and programming means for controlling the swinging of said beam from each of said positions to the other and for predetermining the periods of dwell at each of said positions independently of said adjustably limiting means to provide dissimilar and characteristic periods of illumination and darkness on the opposite sides of said channel respectively, whereby an observer may ascertain with only the naked eye on which side of the center of said channel he is located.

3. Single station range light apparatus for visually indicating to an observer his position in respect to the center of a predetermined channel, comprising a single source of visible light located substantially in a predetermined plane containing the center of said channel and substantially in prolongation thereof in said plane, light beam directing means associated with said light source for focusing the light from said source and directing it as a beam with the area of illumination thereof restricted to a predetermined relatively narrow zone about a center line of the beam and in a lateral direction perpendicular to said plane, means for relatively moving said light source and at least a part of said light beam directing means to swing said beam back and forth between a first position in which it is directed down one side of said channel with the center line of said beam on one side of the center of said channel, and a second position in which it is directed down the other side of said channel with the center line of said beam on the other side of the center of said channel, means for independently adjustably controlling the location of each of said positions so as to control the location of the illuminated sector

and the angular amplitude of the swing of said beam, and programming means for controlling the swinging of said beam from each of said positions to the other and for predetermining the periods of dwell at each of said positions independently of said controlling means to provide dissimilar and characteristic periods of illumination and darkness on the opposite sides of said channel respectively, whereby an observer may ascertain with only the naked eye on which side of the center of said channel he is located.

4. Single station range light apparatus for visually indicating to an observer his position in respect to the center of a predetermined channel, comprising a single source of visible light located substantially in a vertical plane containing the center of said channel and substantially in prolongation thereof in said plane, light beam directing means associated with said light source for focusing the light from said source and directing it as a beam with the area of illumination thereof restricted to a predetermined relatively narrow zone about a center line of the beam and in a lateral direction perpendicular to said plane, means for relatively moving said light source and at least a part of said light beam directing means to swing said beam back and forth between a first position in which it is directed down one side of said channel with the center line of said beam on one side of the center of said channel, and a second position in which it is directed down the other side of said channel with the center line of said beam on the other side of the center of said channel, said light beam directing means including means for independently selectively predetermining the vertical and lateral angular spread of the beam, separate means for adjustably independently determining the angular locations of said positions in respect to the center of the channel respectively, fixed support means for said light apparatus, means for independently adjusting the angular position of the entire range light apparatus in respect to said fixed support means about a vertical axis to coordinate the illuminated area with the limits of the channel to be illuminated, other means for adjusting the angular position of the entire range light apparatus in respect to said fixed support means about a horizontal axis to compensate for the vertical location of the apparatus in respect to the channel to be illuminated, and programming means for controlling the swinging of said beam from each of said positions to the other and for predetermining the periods of dwell at each of said positions independent of other adjusting and predetermining means aforesaid to provide dissimilar and characteristic periods of illumination and darkness on the opposite sides of said channel respectively, whereby an observer may ascertain with only the naked eye on which side of the center of said channel he is located.

5. Single station range light apparatus for visually indicating to an observer his position in respect to the center of a predetermined channel, comprising a source of visible light, light beam directing means associated with said source of light for restricting the area of illumination thereof to a relatively narrow beam, and means for oscillating said beam laterally of said channel between predetermined positions respectively on opposite sides of the center of said channel, said oscillating means including a substantially constant speed prime mover, and motion transmitting means operated by said prime mover and

including spring-actuated, snap-action toggle means of the over-center-throw type for substantially instantaneously relatively moving said light source and at least a part of said light beam directing means to oscillate said beam between its terminal positions aforesaid, and means for controlling the period of dwell of said beam at each of said terminal positions independently of the time of movement from either of said positions to the other.

6. Single station range light apparatus for visually indicating to an observer his position in respect to the center of a predetermined channel, comprising means providing a narrow beam of visible light and including as elements a source of visible light, a reflector and lens means; and means for oscillating the light beam laterally of said channel between predetermined positions respectively on opposite sides of the center of said channel, said oscillating means including a substantially constant speed prime mover, means mounting at least one of said elements for movement about a predetermined axis in respect to the remainder of said elements, a lever mounted for oscillation about said axis, cam means operated by said prime mover for oscillating said lever about said axis, and means mechanically interconnecting said lever and the element which is oscillatable about said axis for oscillating the latter in response to the oscillation of said lever, said mechanical interconnecting means comprising a spring-actuated, snap-action toggle mechanism of the over-center-throw type effective to move said beam substantially instantaneously between its terminal positions, whereby the dwell times at said terminal positions may be controlled by said prime mover in accordance with said cam means to provide dwell positions characteristic in time and frequency substantially independent of the time period for the movement of said beam between said terminal positions.

7. Single station range light apparatus in accordance with claim 5, comprising in addition, independently adjustable stop means for predetermining the terminal positions of the light beam by limiting the relative movement between said light source and at least a part of said light beam directing means, said oscillating means and said stop means being so constructed and arranged that the terminal positions of the light beam are adjustable by said stop means independently of said prime mover and said motion transmitting means.

8. Single station range light apparatus for visually indicating to an observer his position in respect to the center of a predetermined channel, comprising a single source of visible light located substantially in a predetermined vertical plane containing the center of said channel and substantially in prolongation thereof in said plane, light beam directing means associated with said light source for focusing the light from said source and directing it as a beam with the area of illumination thereof restricted to a predetermined relatively narrow zone about a center line of the beam and in a lateral direction perpendicular to said plane, lens means forming a part of said light beam directing means providing a predetermined angular spread for said beam about said center line, means for oscillating said beam in a direction perpendicular to said plane and laterally of said channel between predetermined dwell positions for said beam respectively on opposite sides of the center of said

channel, said oscillating means including a pair of individually energizable opposed solenoids connected to effect a relative movement in one direction and the other respectively between said light source and at least a part of said light beam directing means to oscillate said beam between its dwell positions aforesaid, means for independently adjustably locating the sectors illuminated by said beam at each of its dwell positions respectively by adjustably varying the positions of the center line of said beam at each of said dwell positions in coordination with the center and lateral outside safe limits of said channel to restrict the positions of said beam to predetermined portions of said channel considered safe for use, and programming means independent of said locating means for automatically controlling the time periods during which a visible light beam is directed down one side of said channel and for similarly controlling substantially complementary time periods during which a visible light beam is directed down the other side of said channel, said programming means being constructed and arranged to provide dissimilar and characteristic intermittent periods of illumination and darkness on opposite sides of said channel respectively, whereby an observer may visually ascertain on which side of the center of said channel he is located.

9. Single station range light apparatus in accordance with claim 8, comprising, in addition, holding means effective to retain said light source and said light beam directing means in predetermined relative position to hold said light beam at one of its terminal positions aforesaid when both said solenoids are de-energized, said holding means being ineffective to prevent movement of said light beam from one of its positions to the other upon the energization of the one of said solenoids provided for effecting such movement.

10. Single station range light apparatus in accordance with claim 8, comprising, in addition, permanent magnet means including pole parts arranged in predetermined positions, and an armature member arranged to be moved from one position to another upon the movement of said light beam between its respective terminal positions, said terminal positions of the movement of said armature member being adjacent to said pole pieces.

11. Single station range light apparatus for visually indicating to an observer his position with respect to the center of a predetermined channel, comprising a single stationary source of visible light located at a predetermined point, light beam directing means associated with said light source for restricting the area of illumination thereof to a relatively narrow beam, said light beam directing means including a parabolic mirror reflector so located that the focal point thereof is the point at which the center of illumination of said light source is located, and lens means including at least two lenses respectively selected to give predetermined vertical and horizontal spread angles to said beam, means mounting said mirror reflector for oscillation about a predetermined axis passing through the focal point of said mirror reflector for swinging said beam laterally of said channel between predetermined positions respectively on opposite sides of said channel, a substantially constant speed motor, a cam rotated thereby, and over-center-throw toggle means operated by said cam for swinging said mirror re-

flector about said axis, whereby said beam will be oscillated between its terminal positions in accordance with a predetermined programming schedule which is repeated in successive equal time intervals.

12. Single station range light apparatus in accordance with claim 11, comprising in addition, lampchanging apparatus including a plurality of electric bulbs, constructed and arranged so as to position an operative one of said bulbs at said predetermined point and to move a successive bulb to said point upon the burnout of a bulb at said point, and means for substantially universally adjusting the position of said lamp-changing apparatus so as to locate the center of illumination of an operative bulb at said predetermined point.

13. Single station range light apparatus for visually indicating to an observer his position in respect to the center of a predetermined channel, comprising a single source of visible light, means associated with said light source for collecting light therefrom and directing it as a beam in a predetermined first fixed direction, reflecting means for redirecting said beam to project it in a second direction at a substantial angle to said first direction, lens means providing a predetermined angular spread for said beam about a center line and in a direction laterally of said channel, means for oscillating said beam laterally of said channel between predetermined dwell positions respectively on opposite sides of the center of said channel by oscillating said reflecting means, said oscillating means being effective to vary the angle between said first direction and said second direction, so as to project said beam alternately in two predetermined terminal dwell positions, means for independently adjustably locating the sectors illuminated by said beam at each of its dwell positions respectively by adjustably varying the positions of the center line of said beam at each of said dwell positions in coordination with the center and lateral outside limits of said channel to restrict the position of said beam to predetermined portions of said channel considered safe for use, and means programming the movements of the beam direction changing means aforesaid so as to control the periods of illumination on opposite sides of said channel respectively and so as to give characteristic different intermittent periods of illumination and darkness on opposite sides of said channel respectively.

14. Single station range light apparatus in accordance with claim 13, in which said fixed first direction is located substantially in the plane of oscillation of said beam, whereby the angle of oscillation imparted to said reflecting means is substantially one-half the angular distance between the terminal dwell positions of said beam.

15. Single station range light apparatus in accordance with claim 13, wherein said reflecting means is a plane mirror mounted for oscillatory movement about a predetermined axis, and wherein said light beam oscillating means comprises a substantially constant speed prime mover, a shaft rotated thereby, and means including at least one cam responsive to the rotation of said shaft for oscillating said mirror between its terminal positions at which it directs the light beam down opposite sides of said channel respectively.
